UNITED STATES PATENT OFFICE

2,124,546

HEEL-SEAT FORMING MACHINE

Michele Cuozzo, Lynn, Mass., assignor to United Shoe Machinery Corporation, Paterson, N. J., a corporation of New Jersey

Original application May 22, 1936, Serial No. 81,306. Divided and this application December 31, 1936, Serial No. 118,625

6 Claims. (Cl. 12—31.5)

This invention relates to machines for use in the manufacture of shoes and is illustrated as embodied in a machine for shaping the heel seats of shoes for the reception of heels.

- 5 As disclosed in an application for United States Letters Patent, Serial No. 81,306, filed May 22, 1936, in my name, in order to improve the joints between the counter portions of shoes and heels attached to the shoes, I propose to 10 wipe limited portions of the opposite sides of the counter portion of the shoe toward the heel seat of the shoe, while the heel seat is being shaped by the use of a heel-seat forming mold or by a heel during its attachment to the shoe, and to 15 maintain said opposite sides of the counter portion of the shoe in wiped relation with the mold or heel while the mold or heel is held under heavy molding pressure against the heel seat of the shoe.
- 20 In accordance with a feature of the present invention, the machine illustrated in this application, which is a division of the above-mentioned application Serial No. 81,306, comprises a pair of wipers for engaging limited areas of the 25 opposite sides of the counter portion of a shoe upon a form, and an abutment independent of the wipers, said abutment being arranged to enable the shoe to be moved with relation to said wipers by pressure applied against the heel seat 30 of the shoe until limited by the engagement of said form with said abutment thereby causing limited portions of the sides of the counter portion of the shoe to be wiped toward the heel seat as the shoe is moved toward the abutment.
- 35 The various features of the invention will be understood and appreciated from the following detailed description read in connection with the accompanying drawings, in which

Fig. 1 is a side view, partly broken away, of the 40 illustrated heel-seat molding machine in which a shoe mounted upon a last is positioned, preparatory to operating upon the shoe;

Fig. 2 shows in perspective a portion of the 45 machine and the shoe of Fig. 1 as viewed in the direction indicated by arrows II—II of Fig. 1;

Fig. 3 is a section on line III—III of Fig. 1 after the last upon which the shoe is mounted has been forced against the abutment of the machine under pressure of a mold against the heel seat of 50 the shoe;

Fig. 4 is a perspective view showing the molded heel seat of the shoe illustrated in Fig. 3;

Fig. 5 is a section on line V—V of Fig. 4;

Fig. 6 is a perspective view of a heel the attach-

ing face of which has been coated with thermoplastic adhesive; and

Fig. 7 is a side view of the above machine the mold of which has been replaced by a clamping unit for accommodating a heel which molds the 5 heel seat of the shoe during its attachment to the shoe.

As stated in the above-mentioned application for United States Letters Patent Serial No. 81,306, the front and rear ends 20, 22, respectively (Fig. 1), of the overlasted counter portion of a woman's shoe are commonly higher than the central side portions 24 of the overlasted counter portion, thereby causing the heel of the finished shoe frequently to bridge the side margins of the 15 heel seat. In such a construction, gaps which detract from the appearance of the finished shoe are formed between the sides of the counter portion of the shoe and the rim of the heel. The 20 above defect has been largely overcome by practicing the method disclosed and claimed in the 25 above application.

In order to facilitate practicing the above improved method I have provided an illustrated heel-seat molding machine (Fig. 1) comprising 30 a pair of wipers or supports 26 which are constructed and arranged to be engaged by the opposite sides of the counter portion of a shoe 28 upon a last 30 and to wipe limited portions of the sides of the counter portion toward the heel 35 seat of the shoe while a heel-seat forming mold 32 is forced downward against the heel seat of the shoe. The illustrated mold 32 is heated by an electric coil 33 (Fig. 3) receiving current through leads 34. The operative face 36 (Fig. 35 1) of the mold 32 has a shape substantially the same as that of the attaching face of a heel 40 (Fig. 6) which is to be attached to the shoe.

The wipers 26 comprise work-engaging pads 42 which are made of leather, rubber or other 40 suitable material, and are carried by arms 44 journaled upon screws 46 in threaded relation with the machine frame. The arms 44 are mounted for equal and opposite movement with 45 relation to each other with the provision of intermeshing gear segments 48 and are normally urged toward each other by a spring 50 the ends of which engage within recesses 52 formed in 50 depending extensions 54 of the arms 44. Movement of the wipers 26 toward each other under the action of the spring 50 is limited by the engagement of the depending extension 54 of one 55 of the arms 44 with a nut 56 carried by a bolt 58 hinged to the depending portion of the other arm. The nut 56 may be adjusted into different

positions along the threaded portion of the bolt 58 in order initially to position the work-engaging pads 42 of the wipers in accordance with the width of the shoe.

5 When the shoe is placed upon the wipers 26 with its rear end in engagement with an adjustable back gage 60 (Fig. 1) the last 30 is spaced from an abutment 62 which may be secured to the machine frame in different vertical positions 10 through the provision of screws 64 passing through an elongated slot 66 of the abutment 62 and in threaded relation with the machine frame. The rear face of the abutment 62 and the front face of the machine frame are serrated, as indicated by reference numeral 68 (Fig. 1), in order to insure that the abutment shall not be moved when downward conforming pressure of the mold 32 against the heel seat of the shoe 28 causes the last 30 to be forced against the 15 abutment 62.

It will be noted that in the illustrated construction the fitted heel seat of the shoe is built up by the use of a quantity of thermoplastic adhesive 70 (Fig. 2) which, when in a softened condition, is placed beneath the tab 72 of the sole 74 of the shoe. The tab 72 is provided with an elongated slot 76 through which flows a portion of the thermoplastic adhesive 70 not required to fill the recess 78 formed by the insole and the 30 overlasted margin of the shoe upper, as the mold 32 is forced against the heel seat. The thermoplastic adhesive 70 which passes through the slot 76 is spread over the tab 72 during the heel-seat molding operation to form a heel-attaching face 35 80 (Fig. 4) which is substantially complementary to the attaching face 38 of the heel 40 to be attached to the shoe. Before attaching the heel to the shoe the attaching face of the heel is preferably coated with thermoplastic adhesive and 40 is heated as disclosed in the above-mentioned application for United States Letters Patent Serial No. 81,306.

As the mold 32 is moved down against the supporting pressure of the wipers 26, limited 45 portions of the sides of the counter portion of the shoe are forced by the wipers toward the mold. When the last 30 upon which the shoe is mounted has been forced against the abutment 62 continued downward movement of the mold 32 causes heavy molding pressure to be exerted 50 against the heel seat of the shoe.

The shank 82 (Fig. 1) of the mold 32 slides in a vertical guideway 84 of the machine frame and is provided with a rack 86 meshing with a gear 55 segment 88 which is keyed to a shaft 90 journaled in the machine frame. The mold 32 is normally held in a raised position by a spring 92 having its upper and lower ends secured respectively to a rearward extension of the gear segment 88 and to the machine frame. Secured to the shaft 90 by a set screw 94 is an arm 96 which is linked through a rod 98 to a treadle 100 hinged at its rear end to a fixed block 102. Depression of the treadle 100 causes the mold 32 65 to be moved down, the treadle being retained in its lowered position by a pawl 104 carried by the treadle and normally engaging teeth 106 of the block 102. The mold 32 is held under considerable pressure against the heel seat for a short 70 period during which the thermoplastic adhesive sets and the shape imparted to the heel seat becomes permanent. The operator then withdraws the pawl 104 from engagement with teeth 106 to enable the treadle 100 to be raised under the 75 action of spring 92, by depressing the treadle 108.

The heel-seat molding machine (Fig. 1) may be readily converted into a heel-attaching machine (Fig. 7) in which the heel 40 (Fig. 6), during its attachment to the shoe, conforms the heel seat of the shoe to the desired shape and 5 thus operates as a mold. The heel-attaching machine comprises a slide 110 which corresponds to the shank portion 82 of the mold 32 (Fig. 1) and is provided with a depending portion 112 to which back and tread blocks 114, 116 are pivotally secured. The back and tread blocks 114, 116 are constructed and arranged to engage the rear and tread faces respectively of the heel in order effectively to force the heel under heavy 10 molding pressure against the heel seat of the 15 shoe.

In operating the heel-attaching machine the operator, after placing hot thermoplastic adhesive beneath the tab 72 of the sole as above described, positions the heel 40 in the machine 20 with its tread and back faces in engagement with the respective blocks 116, 114. The treadle is then depressed causing the heel to operate in the same manner as the mold 32 operates against the heel seat, thereby conforming the heel seat 25 to the proper shape. Molding and attaching pressure of the heel against the heel seat of the shoe is maintained until the thermoplastic adhesive has set and the heel seat has been permanently conformed to the desired shape. As 30 the heel is forced against the heel seat of the shoe wipers 26a operate upon the sides of the counter portion of the shoe, as above described in connection with the molding machine, thereby insuring that the sides of the counter portion of 35 the shoe be forced into engagement with the rim of the attaching face of the heel 40. Since the back gage 60a, the abutment 62a, and mechanism for operating the slide 110 and the wipers 26a, are substantially identical with corresponding 40 portions of the molding machine illustrated in Fig. 1, it will not be necessary to describe the construction and operation of these members in detail. Accordingly, the parts of the heel-attaching machine (Fig. 7) which are substantially 45 identical with corresponding parts of the heel-seat molding machine (Fig. 1), have been given, respectively, the same numbers each with an exponent a.

Having described the invention, what I claim 50 as new and desire to secure by Letters Patent of the United States is:

1. In a machine in which pressure is applied against the heel seat of a shoe mounted upon a form to mold said heel seat, a pair of wipers constructed and arranged to be engaged by limited areas of opposite sides of the counter portion of the shoe, and an abutment independent of said wipers, said abutment being arranged to enable the shoe to be moved with relation to said wipers by pressure applied against the heel seat of the shoe until limited by the engagement of said form with said abutment thereby causing limited portions of the sides of the counter portion of the shoe to be wiped toward the heel seat as the 60 shoe is moved toward the abutment.

2. In a machine in which pressure is applied against the heel seat of a shoe mounted upon a form to mold said heel seat, a pair of pivotally mounted wipers constructed and arranged to engage limited areas of opposite sides of the counter portion of the shoe, yieldable means for urging the wipers toward each other, and an abutment into engagement with which the form upon which the shoe is mounted is forced under 75

pressure applied against the heel seat of the shoe, said wipers being constructed and arranged to force limited portions of the sides of the counter portion of the shoe toward said heel seat as the shoe and the form upon which it is mounted are moved toward said abutment.

5. A heel-seat molding machine having, in combination, a pair of wipers mounted for yielding movement away from each other and constructed and arranged to engage limited areas of the respective sides of the counter portion of a shoe mounted upon a form, an abutment, heel-seat molding means, and mechanism for forcing said means against the heel seat of the shoe 10 first to cause the form upon which the shoe is mounted to be moved into engagement with the abutment during which movement the wipers force portions of the sides of the counter portion of the shoe toward said means, and then to cause the heel seat to be conformed to a predetermined shape under heavy molding pressure while the wipers maintain the sides of the counter portion of the shoe in forced engagement with said means.

25. 4. A heel-seat molding machine having, in combination, a pair of wipers constructed and arranged to engage limited areas of the respective sides of the counter portion of a shoe mounted upon a last, a mold mounted for movement toward and away from the heel-seat portion of said shoe, an abutment spaced from the last upon which said shoe is mounted, and means for forcing the mold against the heel seat of the shoe, said wipers being yieldable under pressure of 30 the shoe as said last is moved toward and into engagement with said abutment and being constructed and arranged upon movement of the shoe under pressure of the mold to force limited areas of the sides of the counter portion of the shoe toward said mold, said mold being constructed and arranged to conform the heel seat

of the shoe to a predetermined shape upon the application of heavy molding pressure against the heel seat of the shoe supported through the last by said abutment.

5. A heel-seat molding machine having, in combination, a pair of wipers mounted for yielding movement away from each other, said wipers being constructed and arranged to engage limited areas of the respective sides of the counter portion of a shoe mounted upon a last, an abutment 10 spaced from the last upon which the shoe is mounted, a mold, means for heating the mold, and means for forcing the mold against the heel seat of the shoe first to cause the wipers to force the limited portions of the respective sides of the 15 counter portion of the shoe toward the mold and then to cause the last to be forced with considerable pressure against said abutment while said wipers continue to force said portions toward the mold.

20. 6. A heel-seat molding and heel-attaching machine having, in combination, a pair of wipers constructed and arranged to engage the respective sides of the counter portion of a shoe mounted upon a last, an abutment spaced from the last 25 of the shoe in engagement with said wipers, and means for forcing a heel against the heel seat of the shoe after adhesive has been interposed between the heel and the heel seat, said wipers being yieldable under pressure of the shoe to 30 enable the last upon which the shoe is mounted to be forced against the abutment with considerable pressure, said wipers being constructed and arranged to force limited portions of the sides of the counter portion of the shoe with considerable 35 pressure against the rim of the heel while the shoe is being moved toward said abutment and while the heel is being forced against the heel seat of the shoe under molding and attaching pressure.

MICHELE CUOZZO.
